UNITED STATES PATENT OFFICE.

CHARLES H. THOM, OF LOS ANGELES, CALIFORNIA.

DESIGN FOR A SODA-WATER BOTTLE.

Application filed September 22, 1924. Serial No. 10,875. Term of patent 7 years.

To all whom it may concern:

Be it known that I, CHARLES H. THOM, a citizen of the United States, residing at Los Angeles, in the county of Los Angeles and State of California, have invented a new, original, and ornamental Design for Soda-Water Bottles, of which the following is a specification, reference being had to the accompanying drawing, forming part thereof.

The figure is a view in side elevation of a soda water bottle, showing my new design.

I claim:

The ornamental design for a soda-water bottle, as shown.

CHARLES H. THOM.
